FABRIC ENGAGING DEVICE

Joseph O. Pollack, Chicago, Ill.

Application February 20, 1935, Serial No. 7,366

8 Claims. (Cl. 24—259)

The invention relates to devices adapted to operatively engage collars, cravats, napkins and the like and to hold the articles so engaged in proper position relative to the body of the wearer.

5 The invention has among its objects the provision of improved fabric engaging members and flexible connecting means therefor adapting the device for a variety of uses including the maintenance of the free edges of a collar in fixed relation, the holding of a cravat in its normal position, and the suspension of a napkin or bib from the neck of the wearer.

Another object of the invention is the provision of fastening devices of the kind described which 15 are capable of easy manipulation for securing the same to a garment or other fabric articles, and which are durable, economical of construction, and satisfactory for their intended purpose.

Many other objects and advantages of the 20 construction herein shown and described will be obvious to those skilled in the art from the disclosures herein given.

To this end my invention consists in the novel construction, arrangement and combination of 25 parts herein shown and described and more particularly pointed out in the claims.

In the drawings, wherein like reference characters indicate like or corresponding parts:

Fig. 1 is a front view of a shirt on which is 30 mounted an embodiment of the invention adapted to hold a cravat in normal undistorted position;

Figs. 2 and 3 are respectively plan and elevational views of a fabric engaging member forming a portion of the device shown in Fig. 1;

Figs. 4 and 5 are respectively plan and elevational views of another fabric engaging member forming a portion of the device shown in Fig. 1;

Figs. 6 and 7 are respectively plan and elevational views of an alternative embodiment of a fabric engaging member adapted to be substituted for the member shown in Figs. 2 and 3;

Figs. 8 and 9 are respectively plan and elevational views of an alternative form of fabric engaging member adapted to be substituted for the member shown in Figs. 4 and 5;

Fig. 10 illustrates another embodiment of the invention adaptable to engage and prevent spreading of the free ends of a collar;

Figs. 11 and 12 are respectively plan and elevational views of fabric engaging members forming the ends of the device shown in Fig. 10;

Fig. 13 illustrates the adaptability of the 55 device shown in Fig. 10 as a cravat holder wherein

one end of the device is connected with the cravat and the other end with the overlapping edge of the shirt whereby the cravat is held in normal undistorted position; and

Fig. 14 is a view of still another embodiment 5 of the invention comprising a pair of fabric engaging members adapted for connection with a napkin or bib, the clamp members being connected by a chain of sufficient length to encircle the neck of the wearer.

Referring now more particularly to the drawings, the numeral 10 designates a chain having fabric engaging members 11 and 12 respectively fastened on its opposite ends. The member 11 comprises a pair of slightly flexible bars 16 respectively adapted to engage the opposite sides of the overlapping edge of a shirt 13 and the member 12 comprises a rigid plate 19 and a co-operating normally resilient member 20 respectively adapted to engage the opposite sides of a 20 pleat 14 on the shirt which extends in parallel spaced relation to its overlapping edge. The chain 10 is of sufficient length to extend around the edges and across the front of a cravat 15 and thereby hold the cravat in normal vertical position.

The bars 16 comprising the member 11 provide registering apertures 18 adapted to receive the end link of the chain 10. The bars 16 are firmly 30 fastened together adjacent the apertures 18 by means of clips 17 integrally formed with one of the bars and bent around the edges of the other in such a manner as to hold the bars against relative lateral or longitudinal movement. The 35 bars 16 are normally in contact adjacent their free ends with their extreme free end portions diverging to provide a wedge-shaped recess adapted for easy insertion of a fabric sheet. The intermediate portions of the bars 16 are spaced 40 apart sufficient that the inserted fabric sheet is not clamped between the bars except at the normal contacting point adjacent their free ends. The member 11 is held in position on the garment by the pressure exerted by the bars 16 upon the inserted fabric, the resilience of the bars being such that the member is easily mounted upon and detached from the fabric without manual actuation of the bars other than pushing or pulling 45 upon the members.

The member 12 is constructed to positively engage the inserted fabric to prevent loss of the device in the event of accidental detachment of the frictionally held fabric engaging member 11. 55

For this purpose the member 12 requires positive manual actuation of the resilient member 20 relative to the plate 19 in order that the member may be mounted upon or removed from a fabric article. One end of the plate 19 provides a stem of the same width as the slightly resilient member 20, the stem and member being provided with registering apertures 23 in which the end link of the chain 10 is inserted. The plate 19 and the member 20 are fixedly fastened together adjacent the apertures 23 by means of clips 21. The intermediate portion of the member 20 forms a loop projecting through an aperture 22 in the plate 19 with its outer free end spaced from the plate 19 except at its terminus which is inturned to form a jaw 24 normally contacting with the plate. The clamp member 12 is operatively engaged and disengaged with the pleat 14 by pressing on the loop portion of the member 20 to move the jaw 24 away from the plate 19. The resilience of the member 20 is such that the jaw 24 prevents movement of the member 12 relative to the inserted fabric except by positive actuation of the member 20.

A fabric engaging member 25 shown in Figs. 8 and 9 is adapted as a substitute for the member 11 and comprises a relatively resilient narrow member 29, connected with a relatively rigid wide member 30 by a loop 26, adapted to receive a ring 27 connecting the members with the chain 10. The members 29 and 30 are fastened together adjacent the loop 26 by means of clips 28 integrally formed with and projecting from the member 30. The intermediate portions of the members 29 and 30 are spaced apart as shown, the member 29 terminating in a slightly outwardly curved portion and the member 30 having its free end providing an inturned portion normally contacting with the member 29 and terminating in an outwardly curved portion 31. The diverging free end portions of the members 29 and 30 provide a wedge-shaped recess adapted to receive the edge of the shirt 14. The resilience of the members 29 and 30 is such that the member 25 is adapted to be mounted upon and detached from the shirt front by respectively pushing and pulling upon the member, the latter being thereby frictionally held in position.

A fabric engaging member 38, shown in plan and elevational views in Figs. 6 and 7, respectively, is adapted as a substitute for the fabric engaging positively manipulated member 12. The member 38 comprises a plate 32 connected by a loop 33 with a slightly resilient narrow bar 36.

A ring 34 forming the end link of the chain 10 is positioned in the loop 33. The bar 36 contacts with the plate 32 adjacent the loop 33, then diverges away from and extends back through an aperture 35 in the plate. The free end of the bar 36 is spaced away from the plate 32 except at its extreme end portion 37 which provides a jaw normally contacting with the plate. The member 38 is operable to engage the pleat 14 on the shirt 13 by pressing on the intermediate curved portion of the bar 36 thereby separating the jaw 37 from the plate for insertion and removal of the pleat. The resistance of the bar 36 is such as to permit its manual actuation to release the jaw 37 but is sufficiently rigid that the jaw holds the member in fixed position relative to the fabric except when positively manually actuated.

Another embodiment of the invention is shown in Fig. 10 as comprising a pair of fabric engaging members 41 adapted for frictional engagement

with the free edges of a collar 40. The members 41 are connected by a chain 42 of such a length that the chain is held taut when the members 41 respectively operatively engage the ends of the collar and thereby prevent the edges of the collar from spreading.

The clamp members 41 each comprises a relatively rigid plate 43 and a relatively resilient member 46, connected by a loop 44, in which is inserted the end link of the chain 42. The member 46 and the plate 43 are fastened together adjacent the loop by a pair of clips 45 integrally formed with the plate. The intermediate portion of the member 46 is spaced from the plate 43 and has its free end inturned to contact with the plate adjacent its extremity which diverges from the plate as shown. The resilience of the member 46 is such that it yields to permit mounting of the member 41 on the collar and its removal therefrom, by respectively pushing or pulling on the member, the pressure of the member 46 being sufficient to maintain the members in proper position under the normal tendency of the collar to spread.

The device comprising the members 41 and the chain 42 is also adapted as a cravat holder by engaging one of the members with the overlapping edge of the shirt 13 and the other of the members with the edge of a cravat 15 as shown in Fig. 13. The length of the chain 42 is such that it not only holds the ends of the collar in properly spaced relation but it also holds the cravat in its normal vertical position.

Fig. 14 illustrates a pair of the clamp members 38, constructed as hereinbefore described, and mounted on the ends of a chain 47, the chain being of sufficient length to encircle the neck of a child and the clamp member 38 being adapted to operatively engage a napkin or bib 48. The members 38, being operable only by positive manual manipulation of the bars 36, are especially adapted for this purpose since the bib cannot be detached by pulling thereon and its removal by a child wearing the same is prevented.

Thus it will be seen that the invention embodies improvements in fastening devices of the kind described including novel fabric fastening members, some of which are maintained in place by frictional engagement with the fabric and some by positive jaw action, the fabric engaging members being connected by flexible members of lengths adapting the devices for a variety of uses such as cravat holders, collar fasteners and napkin or bib supporting members.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A fabric engaging member comprising a pair of bars arranged in longitudinal juxtaposition, a pair of clips fixedly fastening said bars together adjacent one end thereof, each of said clips being integral with one of said bars and bent around the other bar in such a manner as to clamp together the portions of the bars engaged thereby, and means adapted for fastening a flexible member to the fixed end of said bars, said bars being in yielding contact adjacent their free ends and

- otherwise spaced apart with their extreme free end portions substantially divergent.
2. A fabric engaging member comprising a pair of bars arranged in longitudinal juxtaposition, a pair of clips fixedly fastening said bars together adjacent one end thereof, each of said clips being integral with one of said bars and bent around the other bar in such a manner as to clamp together the portions of the bars engaged thereby, and means adapted for fastening a flexible member to the fixed end of said bars, said bars being in yielding contact adjacent their free ends and otherwise spaced apart with their extreme free end portions substantially divergent, one of said bars being wider and less resilient than the other bar.
3. A fabric engaging member comprising a pair of bars arranged in longitudinal juxtaposition, a pair of clips fixedly fastening said bars together adjacent one end thereof, each of said clips being integral with one of said bars and bent around the other bar in such a manner as to clamp together the portions of the bars engaged thereby, and a loop member integral with and connecting the fixed ends of said bars, said bars being in yielding contact adjacent their free ends and otherwise spaced apart with their extreme free end portions substantially divergent.
4. A fabric engaging member comprising a pair of bars arranged in longitudinal juxtaposition, a pair of clips fixedly fastening said bars together adjacent one end thereof, each of said clips being integral with one of said bars and bent around the other bar in such a manner as to clamp together the portions of the bars engaged thereby, and a loop member integral with and connecting the fixed ends of said bars, said bars being in yielding contact adjacent their free ends and otherwise spaced apart with their extreme free end portions substantially divergent, one of said bars being wider and less resilient than the other bar.
5. A fabric engaging member comprising a pair of bars arranged in longitudinal juxtaposition, a pair of clips fixedly fastening said bars together adjacent one end thereof, each of said clips being integral with one of said bars and bent around the other bar in such a manner as to clamp together the portions of the bars engaged thereby, a loop member integral with and connecting the fixed ends of said bars, and a ring connected with said loop member, said bars being in yielding contact adjacent their free ends and otherwise spaced apart with their extreme free end portions substantially divergent, one of said bars being wider and less resilient than the other bar.
6. A fabric engaging member comprising a pair of bars arranged in longitudinal juxtaposition, a pair of clips fixedly fastening said bars together adjacent one end thereof, each of said clips being integral with one of said bars and bent around the other bar in such a manner as to clamp together the portions of the bars engaged thereby, a loop member integral with and connecting the fixed ends of said bars, and a ring connected with said loop member, said bars being in yielding contact adjacent their free ends and otherwise spaced apart with their extreme free end portions substantially divergent, one of said bars being wider and less resilient than the other bar.
7. A device of the kind described comprising a pair of fabric engaging members, each of said members comprising a pair of bars arranged in longitudinal juxtaposition, a pair of clips fixedly fastening said bars together adjacent one end, a loop member integral with and connecting the fixed ends of said bars, and a ring positioned in said loop, said clips being integral with one of said bars and bent around the other bar in such a manner as to clamp together the portions of the bars engaged thereby, said bars being in yielding contact adjacent their free ends and otherwise spaced apart with their extreme free end portions substantially divergent, one of said bars being wider and less resilient than the other bar.
8. A device of the kind described comprising a pair of fabric engaging members, each of said members comprising a pair of bars arranged in longitudinal juxtaposition, a pair of clips fixedly fastening said bars together adjacent one end, a loop member integral with and connecting the fixed ends of said bars, and a ring positioned in said loop, said clips being integral with one of said bars and bent around the other bar in such a manner as to clamp together the portions of the bars engaged thereby, said bars being in yielding contact adjacent their free ends and otherwise spaced apart with their extreme free end portions substantially divergent, one of said bars being wider and less resilient than the other bar.

JOSEPH O. POLLACK.
